Primary Examiner — Susan Bennett Hattan*Assistant Examiner* — Marie Fast Horse(74) *Attorney, Agent, or Firm* — Banner & Witcoff, Ltd.(57) **CLAIM**

The ornamental design for an illuminated augmented reality input device, as shown and described.

DESCRIPTION

FIG. 1 is a perspective view of an illuminated augmented reality input device showing our new design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The radiating lines in the figures represent illumination emanating from the end portion of the device. The broken lines seen in FIGS. 1 and 5 depict portions of the illuminated augmented reality input device that form no part of the claimed design.
